UNITED STATES PATENT OFFICE.

ROBERT A. KOHLHEPP, OF WALLINGFORD, CONNECTICUT, ASSIGNOR TO
LANDERS, FRARY AND CLARK, OF NEW BRITAIN, CONNECTICUT.

DESIGN FOR A FERRULE.

SPECIFICATION forming part of Design No. 35,820, dated March 18, 1902.

Application filed February 19, 1902. Serial No. 94,843. Term of patent 7 years.

To all whom it may concern:

Be it known that I, ROBERT A. KOHLHEPP, a citizen of the United States, residing at Wallingford, in the county of New Haven and State of Connecticut, have invented and produced a new and original Design for a Ferrule, of which the following is a specification, reference being had to the accompanying drawings, forming part thereof.

10 Figure 1 is a side elevation of a ferrule for cutlery, showing my new design. Fig. 2 is a plan view of the same.

As shown in the drawings, the ferrule is mainly of an oval form in transverse section or end view. At the middle portion there is 15 a large rounded bead 3, with a smaller bead 4

at each side thereof. A spreading sheaf-like ornament 5 extends longitudinally from each of the beads 4, the tops or spreading ends of the sheaf-like ornaments being crowned with 20 the quarter-bead 6 at the bolster end of the ferrule and by the bead 7 and band 8 at the handle end thereof.

Having described my invention, what I claim as new, and desire to secure by Letters 25 Patent, is--

The design for a ferrule, as herein shown and described.

ROBERT A. KOHLHEPP.
